UNITED STATES PATENT OFFICE

162,270

HANGING WALL SHELF OR SIMILAR ARTICLE

Saul K. Wolff, Long Beach, N. Y.

Application July 6, 1950, Serial No. 10,970

Term of patent 14 years

(Cl. D33—3)

To all whom it may concern:

Be it known that I, Saul K. Wolff, a citizen of the United States, residing at Long Beach, in the county of Nassau and State of New York, have invented a new, original, and ornamental Design for Hanging Wall Shelf or Similar Article, of which the following is a specification, reference being had to the accompanying drawing, forming part thereof.

In the drawing:

Fig. 1 is a top plan view of a hanging wall shelf or similar article, showing my new design;

Fig. 2 is a front elevational view thereof; and Fig. 3 is a side elevational view thereof.

I claim:

The ornamental design for a hanging wall shelf or similar article, as shown.

SAUL K. WOLFF.
